[57] CLAIM

The ornamental design for an electronic sphygmomanometer, as shown and described.

DESCRIPTION

FIG. 1 is a top, front, and left side perspective view of an electronic sphygmomanometer, showing our new design;

FIG. 2 is a top plan view thereof;

FIG. 3 is a front elevational view thereof;

FIG. 4 is a rear elevational view thereof;

FIG. 5 is a right side elevational view thereof;

FIG. 6 is a left side elevational view thereof; and

FIG. 7 is a bottom plan view thereof; and

The broken line showings of the cuff in FIG. 1 and of the pressure bulb in FIGS. 1-7 are for illustrative purposes and form no part of the claimed design.

FIG. 4

FIG. 5

FIG. 6

FIG. 7
